(57) **CLAIM**

The ornamental design for a jig for processing of implant surgical guide, as shown and described.

DESCRIPTION

FIG. 1 is a perspective view of a jig for processing of implant surgical guide showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The broken lines in the drawings are for the purpose of illustrating portions of the jig for processing of implant surgical guide that form no part of the claimed design.
